(57) **CLAIM**

The ornamental design for an LED light, as shown and described.

DESCRIPTION

FIG. 1 is an isometric view of an LED light according to a third embodiment of our new design;

FIG. 2 is a front elevation view of the LED light shown in FIG. 1;

FIG. 3 is a rear elevation view of the LED light shown in FIG. 1;

FIG. 4 is a left elevation view of the LED light shown in FIG. 1;

FIG. 5 is a right elevation view of the LED light shown in FIG. 1;

FIG. 6 is a top plan view of the LED light shown in FIG. 1; and,

FIG. 7 is a bottom plan view of the LED light shown in FIG. 1.
